SANDER BLOCK

Oscar Stucker, Morocco, Ind.

Application May 17, 1949, Serial No. 93,785

4 Claims. (Cl. 51—187)

1

This invention relates to a sanding block, and more particularly to an expandable block for a continuous strip or band of sandpaper or other abrasive or polishing material.

It is an object of this invention to provide a sander block of the kind to be more particularly described hereinafter, which is expandable for tightly stretching a band of abrasive material in such a manner that the entire surface of the abrasive band may be used before the strip is discarded.

Another object of this invention is to provide an expandable sander block of this kind having wedge members insertable between the pair of block sections for pressing the block sections outwardly into contact with the inner surface of the loop of abrasive material engaged thereabout, the stretched loop and the block sections providing a rigid block for use in sanding, polishing or the like.

Still another object of this invention is to provide a sander block of this kind having wedge elements for pressing apart the block sections, the block sections being formed for receiving the wedges within the outside limits thereof, so that the wedges do not extend outwardly beyond the sides of the block and the block sections and wedges being formed for readily extracting the wedges to provide for the changing of the sandpaper looped about the block.

With the above and other objects in view, my invention consists in the arrangement, combination and details of construction disclosed in the drawings and specification, and then more particularly pointed out in the appended claims.

In the drawings:

Figure 1 is a perspective view of a sander block constructed according to an embodiment of this invention;

Figure 2 is a horizontal transverse section taken on the line 2—2 of Figure 1;

Figure 3 is a transverse section taken on the line 3—3 of Figure 1;

Figure 4 is a transverse section taken on the line 4—4 of Figure 1;

Figure 5 is a perspective view of one of the wedge blocks removed from the sander block assembly.

Referring to the drawings, the numeral 10 designates generally a sander block constructed according to an embodiment of this invention for supporting a continuous strip or loop of flexible material, as sandpaper, polishing cloth or the like. The sander block 10 is expandable for engaging the flexible member within the loop for

2

stretching the flexible member to a taut condition when it is to be used for sanding, polishing, or light work.

The sander block 10 is formed of a pair of sander block sections 11 and 12 which are preferably made of wood or other suitable light and hard material. The sander block sections 11 and 12 are substantially rectangular in configuration, though one of the block sections may be formed with a substantially pointed tip, as the pointed tip 14 of the sander block 11, as clearly shown in Figure 1 of the drawings. In any event, the outermost corners or edges of the block sections 11 and 12 will be rounded to provide for the smooth engagement of the flexible member 15 about the corners of the block when the flexible member is stretched over the outer surface of the block sections 11 and 12.

The flexible member 15 shown in the drawings is a loop of sandpaper or emery cloth having a flexible base or strip 16 on which a coating of sand, emery or other suitable abrasive or polishing material 17 is suitably fixed, as by glue.

One of the sander block sections, as the sander block section 12, is formed with a pair of inwardly-opening, longitudinally-extending bores or recesses 18 and 19 opening through the face of the block which is to be positioned in confronting position relative to a similar confronting face of the adjacent block section 11. A pair of pins or dowel members 20 and 21 are fixed on the confronting face of the adjacent block section 11 and extend inwardly therefrom in the direction of the other block section 12 for slidably engagement in the respective recesses or bores 18 and 19. The bores 18 and 19, together with the dowels 20 and 21, constitute the slidably attaching means for slidably securing the adjacent, confronting block sections 11 and 12 together.

A pair of wedge elements 22 are slidably engageable in the space between the confronting block sections 11 and 12, as clearly shown in Figures 1 and 2 of the drawings. The wedge elements 22 are preferably formed of wood, metal or other suitable hard material for engagement between the confronting faces of the adjacent block sections. The wedge elements 22 are formed with a pair of inwardly-converging outer faces 24 and 25 which are adapted to frictionally engage the confronting faces of the adjacent block sections at their outer edges for spreading apart the block sections when the block sections are contained within the flexible loop 15. Each of the wedge elements 22 is formed with a vertical or transverse recess 26 on one of the inclined

faces, as the face 25, the recess 26 providing a finger grip or tool-engaging formation for removing the wedge element when the wedge element is frictionally and tightly engaged between the block sections. One edge of the recess 25, as the edge 26a, will form a shoulder or abutment against which the tool may be engaged for removing the wedge element from between the block sections.

One of the block sections, as the block section 11, is formed with an inwardly-inclined recess 27 on each opposite side thereof at the abutting ends in relation to the block section 12. The inwardly-inclined recesses 27 are inclined inwardly from the outer side of the block section 11 and terminate in the inner face confronting the inner face of the block section 12. The recesses 27 are provided for the insertion of the wedge-retracting or extracting tool for removing the wedges when they are clampingly engaged between the two block sections 11 and 12.

In the use and operation of the sander block 10 described above, the block sections 11 and 12 are slidably connected together by engaging the pins or dowels 20 and 21 of the block section 11 into the recesses 18 and 19 of the other block section 12 and sliding the two block sections together so that their confronting inner faces are in abutting relation. The retracted block 10 is then engaged within a flexible loop, as the loop of sandpaper 15, and then the wedge elements 22 are pressed inwardly between the confronting faces of the adjacent block sections for pressing the block sections outwardly to stretch the flexible member 15 to a taut condition where the flexible member 15 will overlie the entire outer surface of the sander block 10. The pointed ends of the wedge blocks or elements 25 are engaged between the confronting faces of the block sections 11 and 12 and the wedge elements on the opposite sides of the blocks are pressed inwardly as far as they will go to tighten the flexible member 15 about the block. In many instances the wedge elements 22 will be completely disposed inwardly of the side edges of the block sections 11 and 12, so that the outer ends of the wedge elements will be disposed in the block. For retracting or extracting the wedge elements 22 for sliding the flexible member 15 to a different position on the block, a suitable wedge-removing tool is engaged in the recess 27 on one side of the block 10 and in the groove 26 which is positioned in the block 10 in communication with the recess 27 and the tool has been pivoted about the outer side of the block 11 for extracting the wedge elements.

With the use of an expandible block of this kind, spring blocks heretofore used are not required for maintaining the flexible element 15 in a taut condition, and the flexible element will be maintained in the taut condition in all directions of movement of the sander block 10. The formation of the sander block 10 of wood in the manner described above provides for the manufacture of a sander block of this kind which may be manufactured at a low cost and distributed at a reasonable price.

The formation of the sander block provides for the use and application of the block sections 11 and 12, together with the wedge elements 22, for other uses than sandpaper, as uses in polishing or other work where a flexible loop element is adapted to be engaged about an expandible rigid block assembly wherein the block assembly pro-

vides for the application of a smooth and continuous force on the sheet or strip of material to be used.

I do not mean to confine myself to the exact details of construction herein disclosed, but claim all variations falling within the purview of the appended claims.

I claim:

1. An expandible block engageable in a continuous loop of flexible material for holding said material taut about said block comprising a pair of block sections slidably connected together, a pair of tapered spreader elements frictionally engageable between said block sections for spreading the block sections apart upon sliding of said elements inwardly, one of said block sections being formed with intermediate, outwardly-opening cut-out portions on the side edges thereof adjacent the abutting section and adjacent the wedge elements for the insertion of a wedge-retrieving tool.

2. An expandible block engageable in a continuous loop of flexible material for holding said material taut about said block comprising a pair of block sections slidably connected together, a pair of tapered spreader elements frictionally engageable between said block sections for spreading the block sections apart upon sliding of said elements inwardly, one of said block sections being formed with intermediate, outwardly-opening cut-out portions on the side edges thereof adjacent the abutting section and adjacent the wedge elements for the insertion of a wedge-retrieving tool, each of said wedge elements having a tool-receiving recess on one side thereof in communication with the adjacent cut-out portion.

3. An expandible block engageable in a continuous loop of flexible material for holding the material taut about said block comprising a pair of block sections slidably connected together, spreader elements slidably engageable between said block sections for spreading said block sections apart upon sliding of said spreader elements inwardly therebetween, each of said spreader elements having a tool engaging formation thereon for engagement by a tool for sliding said spreader elements from between said block sections.

4. An expandible block engageable in a continuous loop of flexible material for holding the material taut about said block comprising a pair of block sections slidably connected together, spreader elements engageable between said block sections for spreading said block sections apart upon sliding of said spreader elements inwardly therebetween, each of said spreader elements having a shoulder thereon for engagement by a tool for sliding said spreader elements from between said block sections.

OSCAR STUCKER.
